(57) **CLAIM**

The ornamental design for a display screen with graphical user interface, as shown and described.

DESCRIPTION

A portion of the disclosure of this patent document contains material to which a claim for copyright protection is made. The copyright owner has no objection to the reproduction of the patent document or the patent disclosure, as it appears in the U.S. Patent Office records, but reserves all other copyright rights whatsoever.

The FIGURE is a front view of the display screen with graphical user interface showing our new and ornamental design. The broken line showing of a portion of the display screen and other elements form no part of the claimed design.
